UNITED STATES PATENT OFFICE.

FRITZ SCHMIDTMANN, OF DUSSELDORF, GERMANY.

FOLDING TABLE.

973,220.

Specification of Letters Patent. Patented Oct. 18, 1910.

Application filed September 9, 1909. Serial No. 516,944.

To all whom it may concern:

Be it known that I, FRITZ SCHMIDTMANN, a citizen of Germany, residing at Dusseldorf, Germany, have invented new and useful Improvements in Folding Tables, of which the following is a specification.

This invention relates to a folding table which may be readily unfolded, extended or collapsed, and which is so constructed that 10 it will be securely braced when open while occupying a minimum space when folded.

In the accompanying drawing: Figure 1 is a perspective view of my improved table, showing it unfolded, Fig. 2 a detail of part 15 thereof, and Fig. 3 a side view partly in section showing the table collapsed.

The table top is composed of two sections *d*, *e*, connected by hinges *n*. Each section is preferably formed of several layers of 20 wood, which are glued together with their grain crossing each other, so as to insure strength. To the inner ends of plates *d*, *e* are hinged legs *a*, to the lower ends of which are in turn hinged braces *c*. The two braces 25 *c* are connected to each other near their lower ends by an articulated strut *s*. The

upper ends of braces *c* are hinged at *h'* to the inner reduced sections *h* of a pair of extension leaves *f*, *g* slideable in ways *l* of top plates *d*, *e*. When the leaves are drawn out, 30 braces *c*, will lift upper faces of leaves *f*, *g* flush with the corresponding faces of plates *d*, *e*, as soon as the inner edges of the leaves clear the outer edges of the plates. Resilient supports *i*, assist in sustaining the inner ends 35 of leaves *f*, *g*, while folding legs *k* serve to support the outer ends thereof.

I claim:

A table provided with a pair of hinged top plates having ways, a pair of leaves 40 having inner reduced ends and slideable in said ways, legs hinged to the inner ends of the plates, an articulated strut connecting the legs, and braces hinged to the lower ends of the legs and to the inner ends of the 45 leaves.

Signed by me at Barmen, Germany, this 12th day of August 1909.

FRITZ SCHMIDTMANN. [L.s.]
